UNITED STATES PATENT OFFICE.

HAROLD D. REGAR, OF READING, PENNSYLVANIA.

DESIGN FOR A CARBON-HOLDER.

58,162.

Specification for Design. Patented June 14, 1921.

Application filed September 9, 1920. Serial No. 409,259. Term of patent 14 years.

To all whom it may concern:

Be it known that I, HAROLD D. REGAR, a citizen of the United States of America, residing in the city of Reading, county of Berks, and State of Pennsylvania, have invented a new, original, and ornamental Design for a Carbon-Holder, of which the following is a specification, reference being had to the accompanying drawing, forming a part thereof.

In the drawing:—

Figure 1 is a front elevational view of my new design for a carbon holder, and Fig. 2 a side elevational view thereof.

I claim:

The ornamental design for a carbon holder, as shown.

HAROLD D. REGAR.
